Geo. P. Kimmel
ATTORNEY.

UNITED STATES PATENT OFFICE

LOUIS CURTIS JOHNSON, OF FAYETTE, ALABAMA

STRINGED MUSICAL INSTRUMENT

Application filed September 11, 1928. Serial No. 305,211.

This invention relates to a fretted, stringed musical instrument and has for its object to provide an instrument of such class, in a manner as hereinafter set forth for producing a fine quality of tone when played and more particularly for enhancing the quality of the tones produced by a mandolin or guitar.

Further objects of the invention are to provide in a manner as hereinafter set forth a fretted, stringed musical instrument which is simple in its construction and arrangement, strong, durable, compact, expeditiously arranged and readily supported in position to be played, conveniently played to produce tones pleasing to the ear, pleasing in appearance, capable of being toned in a convenient manner, and inexpensive to manufacture.

With the foregoing and other objects in view the invention consists of the novel construction, combination and arrangement of parts as hereinafter more specifically described and illustrated in the accompanying drawings wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a top plan view of a musical instrument in accordance with this invention.

Figure 2 is a side elevation thereof.

Figure 3 is a longitudinal sectional view.

Figure 4 is a transverse sectional view.

The instrument includes a hollow body portion or box of any suitable contour and as illustrated by way of example, is of rectangular contour of the desired length and width. The body portion is formed with a flat bottom for seating on the legs of the player or upon a support when one desires to play the instrument.

The body portion is generally indicated at 5 and comprises a pair of end walls 6, 7, a pair of side walls 8, 9, a bottom 10 and a top 11. The side and end walls are of corresponding height and secured upon the upper face of bottom 10 adjacent the side and end edges

thereof. The top 11 has bevelled or curved side and end marginal portions 12, 13 respectively to provide the top of the sides and ends of the body portion rounded. The top 11 is secured to the side and end walls and projects laterally therefrom to align with the side and end edges of the bottom 10. The body portion provides a chamber 13' having a pair of outlets 14, 15 which are provided by spaced, aligning circular openings of appropriate diameter formed in the top 11 and which are intersected at the diametrical centre thereof by the longitudinal median of top 11.

Secured to the upper face of top 11, at the longitudinal median of the latter is a supporting bar 16 which extends from one end to the other end of said top and has its ends oppositely bevelled as at 17, 18. The bar 16 is of a width materially less than the diameter of and extends across the openings 14, 15 at the diametric center of the latter. The height of bar 16 is materially greater than the thickness of top 11. Secured upon the upper face of bar 16, at each end thereof is a transverse bridge-piece 19 of tapered cross section. Preferably the bar and bridge pieces are of wood, but it is to be understood that any desirable material may be employed. The outer side faces of the bridge pieces form continuations of the bevelled ends of the bar.

The preferred number of strings employed in connection with the instrument is four, but this number can be increased if desired. The strings are indicated at 20, 21, 22 and 23 and are suspended over and retained normally in spaced relation with respect to bar 16 by the bridge pieces 19. The strings are disposed in parallel spaced relation and retained at such position by the bridge pieces 19.

Projecting outwardly from the bevelled end 17 of bar 16 is a series of screws or pins 24 for anchoring one end of the strings to said end 17 of bar 16. Rotatably mounted in and projecting from the bevelled end 18 of bar 16 is a series of tuning keys 25 for the strings. The strings are positioned to extend against the bevelled ends 17 and 18 and outer side faces of the bridge pieces 19.

The upper face of bar 16 has secured there-in a series of spaced transversely extending frets 26. The strings are normally arranged in spaced relation with respect to the frets.

5 The front string, indicated at 20, is the note string and the remaining strings are tuned to correspond with the first string. The coarse end of the music is at the end opposite the keys. The strings are held for the 10 purpose of obtaining the chord with the left hand, and the strings are picked with the right hand. The music is all played on the first string and the other strings are used to make the chord or to time the first string with. 15 The tone produced is better than that of a guitar or mandolin.

What I claim is:

1. A stringed musical instrument comprising a rectangular hollow body portion having 20 a pair of spaced, opposed openings in the top thereof, a fretted supporting bar secured upon the top, and of the same length as the length of the body portion, said bar extending across said openings at the diametric center of the 25 latter and of a width less than the diameter of the openings, a pair of spaced bridge pieces mounted upon the upper face of the bar transversely of the latter, strings anchored at one end to one end of the bar and seating on said 30 bridge pieces, and tuning keys connected to the other end of the bar and to the other end of the strings.

2. A stringed musical instrument comprising a rectangular hollow body portion having 35 a pair of spaced, opposed openings in the top thereof, a fretted supporting bar secured upon the top and of the same length as the length of the body portion, said bar extending across said openings at the diametric center 40 of the latter and of a width less than the diameter of the openings, a pair of spaced bridge pieces mounted upon the upper face of the bar transversely of the latter, a set of four parallel strings anchored at one end to one 45 end of the bar and seating on said bridge pieces, one of the outer of said strings constituting the note string and upon which the music is all played and the other of the strings making the chord, and tuning keys connected 50 to the other end of the bar and to the other end of the strings.

3. A stringed musical instrument comprising a hollow body portion having a pair of spaced, opposed openings in the top thereof, 55 said openings disposed at the longitudinal median of said top, a fretted supporting bar secured upon and co-extensive with the top of the body portion, extending across said openings at the diametric center of the latter 60 and of a width less than the diameter of the openings, spaced bridge pieces mounted upon the upper face of the bar transversely of the latter, said bridge pieces positioned at the ends of said bar, strings anchored at one end 65 to one end of the bar and seating on said

bridge pieces, and tuning keys connected to the other end of the bar and to the other end of the strings, said bar co-extensive with said body portion.

4. A stringed musical instrument comprising a body portion, a supporting bar secured upon the top of the latter and having its upper face provided with spaced transversely extending frets, a pair of spaced transversely extending bridge pieces mounted upon the upper face of the bar at the ends thereof, a set of four spaced parallel strings, one constituting a note string upon which all the music is played and the other making the chord, said strings seating on said bridge pieces, means at one end of said bar for anchoring one end of the strings thereto, and tuning keys connected to the other end of the bar and to the other end of the strings.

In testimony whereof, I affix my signature hereto.

LOUIS CURTIS JOHNSON.
